Des. 235,380
Patented June 10, 1975

235,380

HAND HELD POWER UNIT FOR MASSAGING DEVICES

Samuel L. McNair, Overland Park, Kans., assignor to
Dazey Products Co., Kansas City, Mo.

Filed Aug. 28, 1973, Ser. No. 392,261

Term of patent 14 years

Int. Cl. D28—03; D24—99

U.S. Cl. D83—1 T

Fig. 1.

Fig. 2.

Fig. 3.

Fig. 4.

Fig. 5.

FIG. 1 is a top plan view of a hand held power unit for massaging devices showing my new design;

FIG. 2 is a side elevational view of same, the other side being substantially the same in appearance;

FIG. 3 is an end elevational view of same taken from the right end of FIG. 2;

FIG. 4 is an end view of same taken from the left end of FIG. 2; and

FIG. 5 is a bottom plan view of same.

I claim:

The ornamental design for a hand held power unit for massaging devices, as shown and described.
